UNITED STATES PATENT OFFICE.

EUGENE A. SPAULDING, OF PORTLAND, MAINE.

HUMIDIFIER.

Application filed March 12, 1928. Serial No. 260,981.

My invention relates to apparatus employed in humidifying the interiors of such places as mill rooms, shops or halls.

It is a well established fact that the proper conditioning of the air, especially with respect to its per cent of humidity, in the work-rooms of typographical establishments and textile mills, to cite two instances, plays a very important and consequential part in their operation and particularly in the matter of procuring increased production.

The humidifying of enclosed spaces on an extensive scale has, heretofore, been a somewhat expensive undertaking, due largely to the fact that apparatus required for this purpose, of the highest efficiency and of moderate cost was not obtainable.

In the conception of the present invention, the general object I have sought to attain is the production of a thoroughly practicable, economically operable, water-vaporizing contrivance, adaptable for use in any one of numerous situations requiring the humidification of confined air.

With this object in view I have devised and constructed novel apparatus by the use of which I am able to transform into vapor a relatively large proportion of the water delivered to the humidifier—resulting in a great saving of the humidifying medium.

Among other objects relating more specifically to the invention are—

First: A draft-tube providing an enclosed air passage from end to end of the humidifier.

Second: Normal impact of the air against the water covering the side of the distributing disc tending to smooth it out into a thin film before being impacted on the impeditive elements.

Third: A revoluble impeller disc which impacts with the partially vaporized water moving from the opposite direction, completing its disintegration into vapor.

Fourth: Provision for accelerating the movement of the vapor laden air just previous to its exit from the humidifier.

The foregoing epitome discloses the principal objects of my invention; others, however, will be apparent from the description found hereinafter in the specification when taken in connection with the accompanying drawings which I have prepared for the purpose of illustrating my invention.

In the drawings,—

Fig. 1 is a side elevation of my humidifier;

Figs. 2 and 3 are half end views of the larger and smaller ends, respectively, of the preferred design of humidifier;

Fig. 4 is a longitudinal, central sectional elevation thereof;

Fig. 5 is a fragmentary plan view of portions of the device showing particularly the relative location of the water-delivery pipe with respect to the distributing disc;

Fig. 6 is a fragmentary plan view of the impeditive sleeve;

Fig. 7 is a diagrammatical view showing how the mechanical elements co-act to vaporize the water, and

Fig. 8 is an alternative design of the outer casing.

Similar characters of reference are employed to identify like or corresponding parts in all the views of the drawings.

Referring to the drawings, 1 represents the outer casing, or as it might be termed, the draft-tube, which is open at both ends and extends the full length of the humidifier.

The form of this outer casing is susceptible of modification. It may be made straight with short flaring ends as shown in Fig. 8, but for certain reasons I prefer to construct it of a form as illustrated in Figs. 1 and 4, which provides for an enlargement of the exit end, the intermediate portion being of frusto-conical outline.

In a frame 2 within the casing I mount the motor 3, the end 4 of its shaft carrying the blower fan 5 capable of drawing air into and forcing it through the draft-tube. Enclosing a portion of the motor is a frusto-conical shaped casing 6, the larger end of this inner casing being properly supported by the bolts 7.

Within the annular space 8 and similarly supported by the bolts 7, is the impeditive sleeve 9 having on its periphery a plurality of obliquely set blades 9'. As seen in Figs. 6 and 7 these blades are quite openly spaced for reasons hereinafter to be explained.

On the end 10 of the motor shaft are secured two discs, the inner one 11 serving as the water distributing element, and the outer one 12 acting in a two-fold capacity—first, to break up the already partially vaporized water into a finer mist, and secondly, to accelerate the movement of the air

laden with this vaporous medium and force it with an increased velocity into the space to be humidated. I provide a space S between the two discs, which, principally for 5 acquiring greater stiffness of the parts are dished, although so far as my invention is concerned they may be made flat throughout.

For a short distance inwardly from its 10 periphery the disc 11 is made flat and this portion rotates in a transverse plane cutting the blades 9'. The periphery of this disc is in separate but quite close relation to the blades.

15 The disc 12 is larger than the disc 11, its diameter being slightly less than that portion of the interior of the draft tube adjacent it, and on its periphery are a plurality of blades 12' set at such an angle with the axis 20 of the draft tube as will cause, preferably, an accelerated movement of the air when it impinges on the blades.

Extending upwardly from some source of water supply under proper control of suitable delivery apparatus, which, however, forms no part of my present invention, is the water supply pipe 13, the upper end being bent to facilitate the localizing of the water as it is delivered to the slower moving 30 portion of the distributing disc,—which is near its axis. To provide against water flowing to the motor bearing, I supply the collar 14 which traps the water until it eventually passes outwardly by centrifugal force 35 along the side of the disc.

The humidifier may be supported in any convenient manner, as by the bracket 15 which is secured to a post or beam in the room in which the apparatus is to operate.

40 Beneath the outer casing is a drip-pan 16, also supported by the bracket 15. Into this pan any surplus water not vaporized in the humidifier may fall and be taken away through the pipe 17.

45 In hygrometrically controlled water supply devices for humidifying systems, it is desirable to pass moving air across the hygrometric element so as to obtain quicker action thereof in response to any changes in 50 humidity of the air.

So as to make provision for this, I punch or shear a hole 18 through the side of the outer casing leaving the sheared portion 19 intact but bent inwardly at an angle which 55 will deflect a certain amount of the rapidly moving air in the draft tube outwardly and into contact with the hygrometric element.

In describing the action of my humidifier when operating, let it be assumed that the 60 motor is running and that water in the proper amount is being discharged from pipe 13 forming a coating over the side of the distributing disc 11 which will, through centrifugal force be driven along and then 65 off the side of the disc.

The fan 5 is providing a continuous current of air from the room and passing it through the draft tube, part of this air travelling near the outer margins of the annular space 8 but a considerable portion deflecting 70 on the frusto-conical member 6 into the annular space 20 and against the coating of water on the flat portion of the disc 11. This has the effect of flattening out the liquid 75 into a thin film on the disc, from which it is immediately released, centrifugally, and strongly impacted against the impulsive blades 9'.

This feature is an important one for the 80 reason that the thin sheet of water cut by the blades is much more easily and thoroughly broken up or disintegrated into fine particles of spray or mist than could a more dense and bulky body of water released from 85 the distributing disc.

By reference to Fig. 7 it will be observed 90 that the blades 9' are so spaced, relatively, and their angularity with respect to the axis of the cone so established, that water thrown off the disc 11 in tangential lines will impact 95 on their sides and be deflected in a direction substantially opposite from that in which the disc is rotating.

Were there no means provided to further 95 act on the humidifying medium, which at this time is seldom wholly vaporized, it would pass into the room in substantially the same condition as it was when leaving the impulsive blades.

This situation is taken care of by the impeller disc 12, which, although revolving at the same axial speed as does the blower fan 5, has greater peripheral velocity, due to its being larger in diameter; and with the relative pitch angles of the blades in the two 105 elements, 5 and 12, similar, the latter would naturally accelerate the air after its impingement therewith.

It is obvious, also, that the movement of 110 the air could be retarded by changing the pitch angle of the blades 12' if such a departure from the preferred plan was thought advisable.

Reverting to Fig. 7, it will be noticed that 115 the water coming off the distributing disc 11 travels in a direction coincident with the line x and is then deflected by the blades 9' in a direction indicated by line y . Air driven forwardly by the blower fan 5 forces 120 this water or vapor into contact with the revolving blades 12' which are moving in an opposed direction (see arrows) and the meeting of the two elements,—the water and the blades causes a violent impact therebetween, and also again reverses the direction of 125 movement of the water, as shown by line z .

This arrangement thus supplies two stages 130 of air propulsion,—the first delivered from and produced by the blower fan 5 which furnishes the bulk or body of air in which

the humidifying medium is partially vaporized and suspended, and the second, which, through the agency of the impeller disc 12, accelerates the air movement after a thorough 5 disintegration of the liquid element has been effected. It further provides two reversals of movement of the water, transversely of the humidifier, previously to its being discharged therefrom.

10 The last forward impulse given the vapor by the impeller tends to produce a more widespread absorption of the moisture by the air throughout the room,—vastly more, in fact, than if the blower fan 5 was solely 15 depended on for this service.

I lay considerable stress on the functional importance of the impeller disc 12, for through the agency of this element, more, perhaps, than to any one of the others, has 20 the practical success of the humidifier been attained.

As I stated in my preamble, the outer casing of the humidifier may be fashioned in other forms and the one I elected to choose as 25 the preferred embodiment of my invention.

For instance, I may take advantage of the lower cost of production involved in manufacturing the humidifier casing in the form of a substantially straight cylindrical member, in which case slight modifications in the 30 design of the interior structure might be necessary,—as a change in the pitch angle of the blades of the impeller disc, or a more acute angle given the taper of the member 6, 35 and possibly other changes, any and all of which, however, being conformable to the broad meaning and intent of the invention and coextensive with the appended claims.

Having thus described in detail the novel 40 structural features of my humidifier and the advantages accruing in the practical operation thereof, what I claim and desire to secure by Letters Patent is:—

1. A humidifier, comprising an outer, continuous casing, a blower fan within and at one end of said casing, a revoluble water-distributing disc located interiorly of said casing and in axial alignment with the axis of said blower fan, means to conduct moving 45 air to the outlying, border portions of the side of said disc, means to conduct water to the side of said disc, and means whereby the direction of movement of the water passing off said disc through centrifugal force may be twice reversed, transversely of the axis of said disc and the speed of the water and the vapor therefrom may be accelerated before being discharged from out of said casing.

60 2. A humidifier, comprising an outer cylindrical casing, means whereby air may be rapidly moved through said casing from the inlet toward the outlet end thereof, a revoluble water-distributing disc, means 65 whereby water may be conducted to the side

of said disc, means to rotate said disc, means whereby the water moving outwardly along the side of said disc may be subjected to a strong impingement of the rapidly moving air, means adapted to resist the movement of 70 the water centrifugally thrown from off said distributing disc, and a revoluble impeller disc having on its periphery a plurality of obliquely set blades, said blades being adapted to complete the disintegration of 75 the water into vapor and to force the latter at an accelerated speed out of said humidifier.

3. A humidifier, comprising an outer casing, a blower fan disposed within and at one 80 end of said casing, means to actuate said blower fan, a rotatable water-distributing disc within said casing, means to conduct water to said disc, an inner casing within said outer casing, providing therebetween an 85 annular space, said inner casing being so located as to direct a flow of rapidly moving air from said blower fan into strong impingement with the outlying, border portions of the side of said disc, and an impedi- 90 tive element comprising a plurality of obliquely set blades positioned outwardly of but in close relation to said distributing disc, and means to rotate said disc.

4. A humidifier, comprising an outer, continuous casing, a blower fan within and at one end of said casing, means to rotate said blower fan, a rotatable water-distributing disc within said casing, an inner casing disposed in spaced relation with said outer casing 95 whereby an annular space therebetween is provided, a fixed sleeve disposed within said annular space, a plurality of obliquely set blades on the periphery of said sleeve, said blades being positioned outwardly of 100 and in the same transverse plane as is said distributing disc, an impeller disc, a plurality of obliquely set blades on the periphery of said impeller disc, the angle of pitch of said blades being such as to produce an 105 acceleration of the air and vapor passing outwardly of said humidifier.

5. A humidifier, comprising an outer, cylindrical casing, open at both ends, a blower fan operable in one end of said casing, an 110 inner casing adapted to provide, in conjunction with said outer casing, an annular space within said humidifier, a revoluble water-distributing disc, one side thereof lying adjacent to and disposed transversely of one 115 end of said inner casing, means to rotate said disc, conveying means to conduct water to the side of said distributing disc, a sleeve positioned within said beforementioned annular space and adapted to form, with said 120 inner casing, a second annular space through which moving air from said blower fan may be impacted against the marginal side portions of said water distributing disc, a plurality of impeditive blades on the periphery 125 of said water distributing disc, a plurality of impeditive blades on the periphery 130

of said sleeve, the face of each blade being disposed at such an angle with a radial line through said disc as will deflect water thrown centrifugally from said disc in a backward direction, transversely of said outer casing, a revolute impeller disc located adjacent and outwardly of said water-distributing disc, and a plurality of blades on the periphery of said impeller disc, the 10 face of each blade being set at a pitch angle with the axis of said disc such as will accelerate the air passing through said outer casing and reverse the direction of movement of the water and vapor after being deflected 15 from the faces of the said impulsive blades.

6. A humidifier, comprising an outer, cylindrical casing, a blower fan in one end thereof, an inner casing, forming together

with the said outer casing an annular space, a revolute water-distributing disc, a plurality of impulsive elements arranged outwardly of and disposed in the same plane as the said water-distributing disc, means to conduct water to the side of said disc, a revolute impeller disc adjacent to but in separated relation to the said water-distributing disc, and a plurality of blades on the periphery of said impeller disc, said blades being so disposed within said outer casing that all water and vapor thrown off said distributing disc shall be subjected to impaction by said blades before passing outwardly from said outer casing. 20 25 30

In testimony whereof I affix my signature.

EUGENE A. SPAULDING.
